CLAIM

The ornamental design for a starry sky projector, as shown and described.

DESCRIPTION

FIG. 1 is a front, right side, top perspective view of a starry sky projector showing the claimed design;
 FIG. 2 is a front elevational view thereof;
 FIG. 3 is a rear elevational view thereof;
 FIG. 4 is a left side elevational view thereof;
 FIG. 5 is a right side elevational view thereof;
 FIG. 6 is a top plan view thereof; and,
 FIG. 7 is a bottom plan view thereof.

The broken lines in the drawing depict portions of the starry sky projector that form no part of the claimed design.
